CLAIM

The ornamental design for an optical sensor blood flow chamber, as shown and described.

DESCRIPTION

FIG. 1 is a perspective view of the blood flow chamber.

FIG. 2 is a front view of the blood flow chamber as shown in FIG. 1.

FIG. 3 is a top plan view of the blood flow chamber as shown in FIG. 1.

FIG. 4 is an elevational view taken from the left side of the blood flow chamber as shown in FIG. 1.

FIG. 5 is an elevational view taken from the right side of the blood flow chamber as shown in FIG. 1.

FIG. 6 is a bottom plan view of the blood flow chamber as shown in FIG. 1; and,

FIG. 7 is a back view of the blood flow chamber as shown in FIG. 1.

The broken lines in FIGS. 1, 4 and 5 are included for the purpose of illustrating portions of the optical sensor blood flow chamber that form no part of the claimed design.
